UNITED STATES PATENT OFFICE.

ALFRED HERBERT GIBSON, OF HARROGATE, ENGLAND.

PARTITIONED RECEPTACLE.

1,144,835.

Specification of Letters Patent. Patented June 29, 1915.

Application filed June 2, 1913. Serial No. 771,220.

To all whom it may concern:

Be it known that I, ALFRED HERBERT GIBSON, a subject of King George V of Great Britain, residing at Harrogate, in the county 5 of York, England, have invented certain new and useful Improvements in Partitioned Receptacles, of which the following is a specification.

My invention relates to the division and 10 subdivision into sections or compartments of variable dimensions of drawers, boxes, cabinets, shelving and other receptacles, hereinafter referred to as drawers and boxes.

The invention consists broadly, irrespec- 15 tive of the size of the drawer or box, in making provision for variable division and subdivision into, and for inclosing, compartments of rectangular areas, the four sides of which are all vari- 20 able in length by multiples of a convenient standard unit dimension, the engagement of parts in the required multiple unit positions being, on account of cheapness of production, preferably effected by a system of 25 slots of any suitable section or shape of simple or compound nature, the invention consequently involving standardization of parts. When means of engagement other than slots are employed the parts are 30 brought into positions identical with those as if slots were present and as hereinafter set forth.

For dividing and subdividing a standard- 35 ized rectangle there are provided movable partitions of standardized lengths which are made in lengths differing by an equal increment, such increment being equal to the standard of measurement as hereinafter defined and which partitions are also made in 40 various heights. The partitions are preferably of two classes, the main or primary partitions being generally of thicker mate- 45 rial than the secondary or slab like partitions, and the primary partitions being also usable without the secondary partitions.

The standardization of parts, coupled 50 with the multiple unit variability principle, permits of the same standardized partitions being used in drawers or boxes of any and 55 various dimensions provided a rectangle of any one of a series of like standardization is first created within, or formed by, the drawer or box. The invention consequently gives great and general utility. Cheapness of production is also another important consequence of the standardization of parts

owing to large quantities of the same dimensions being manufactured at one time.

There might be employed two or more different units or standards, provided all 60 the units were multiples of the smallest unit employed. Such an arrangement would, however, be of doubtful advantage because the smallest unit might just as well be adopted as the standard unit.

Though the invention makes provision for the use of movable partitions of stand- 65 ardized various lengths in a drawer or box, it will be obvious that in some drawers or boxes some or all of the partitions in use 70 therein may happen to be of equal length, but partitions of other equal lengths or of other various lengths provided they are of the same standardization could at any time be inserted if desired. The capability, as 75 herein set forth, of creating compartments the four sides of which may vary by multi- 80 ples of a standard unit dimension, confers upon the user the power to divide and sub- divide a drawer or box to suit his imme- 85 diate convenience or present requirements, which may vary from time to time, the va- riation possible in any direction being nec- essarily limited to multiples of the said 90 standard unit dimension.

In the drawings, Figure 1 is a plan view of a receptacle constructed according to this 95 invention. Fig. 2 is also a plan view of a receptacle, but shows a modification in the arrangement of its partitions.

In the embodiments illustrated, the vari- 100 ous parts are brought into engagement at the required multiple unit positions by a suitable system of slots, of the same depth, equally spaced apart, with the exceptions 95 hereinafter stated, formed in the material of the engaging parts, or consisting of mov- 105 able single slotted members adapted for en- gagement at the required multiple unit po- sitions, the slots being vertically formed to the mouth of the receptacle. The shape of the slots is preferably rectangular, but angular, dovetail or other suitable shape may be employed if desired. When a dove- tail slot system is used the wider part of 110 the slot may be either at the mouth or at the bottom of the slot.

The distance between the centers or mid- 110 dle lines of adjacent slots is termed the standard of measurement adopted or the standard unit dimension, and the distance between the near edges of adjacent slots is

termed the fixed or standard distance between the slots. The standard of measurement is therefore equivalent to the fixed or standard distance between the slots plus the width of a slot at its mouth, and owing to the thickness of material is greater than the length of a compartment side of unit length. Slots 2 are formed in the standardized rectangle 1 at any suitable equal distances apart, and similar slots 4 are formed at like distances apart on one or both sides of the primary partitions 3. If the mouths of the slots be of the same width as the thickness of the material of the slotted partitions, the eight corner slots of the standardized rectangle are formed at the same distance from their respective corners as the fixed distance between the other slots, and the slots nearest to the ends of the slotted partitions 3 are formed also at the same fixed distance from the ends thereof plus allowance for the engaging portion. When partitions are placed in position they therefore always run parallel to the front and back, or to the sides of the rectangle. If the mouths of the slots are of less width than the thickness of the material of the slotted partitions 3, and such partitions are to be capable of running in both directions in the rectangle 1, and have ordinary tenons 5 with an equal shoulder 5' at each side thereof, or tapering ends 3^a, as shown in Fig. 1, the eight corner slots 2^a are formed at a distance from their respective corners equal to the fixed distance between the other slots less the horizontal width of the shoulder of the tenon, or if the partitions have tapering ends, as shown at 3^a, then as if a tenon and shoulders were present. The slots 4' nearest to the ends of the slotted partitions 3 are formed also at the same lesser distance from the shoulder of the tenon, and consequently when partitions are placed in position they run parallel to the front and back, or to the sides, of the rectangle. The slab partitions are represented by 6.

If, with the same type of tenon, and as shown in Fig. 2, it is not necessary for the

slotted partitions 3 to be capable of running in both directions in the rectangle 1, the end slots 4' of the slotted partitions may be formed at the same distance from the shoulders of the tenons as the fixed distance between the other slots, and, if so formed, four corner and opposite slots 2^b of the rectangle are also formed at the same fixed distance from the respective corners, the remaining four corner slots 2^c being formed at the aforementioned lesser distance from the corners. The use of slab partitions 6 along with slotted partitions 3 is always necessary to obtain multiple unit variability in all directions when slotted partitions are only capable of running in one direction.

The horizontal width of a shoulder of a tenon at the ends of a slotted partition is not necessarily equal to the depth of a slot.

What I claim as new and desire to secure by Letters Patent is:—

The combination with a rectangular receptacle, having all its four inner sides formed or provided with slots spaced at equal distances apart with the exception of the slots nearest the corners which said slots are placed at distances from the corners less than the standard distance between the near edges of a pair of the other slots: of removable partitions of standard lengths having a tenon at each end adapted to fit the slots in the drawer or cabinet, an equal shoulder on each side of said tenon, and slots in both sides of said partitions, corresponding in spacing and formation to the slots in the sides of the drawer or cabinet, the slots nearest the end of a partition being formed at a distance from the shoulder, measured to the near edge of the slot, equal to the standard distance between the other slots less the horizontal width of the shoulder.

In testimony whereof I affix my signature in the presence of two witnesses.

ALFRED HERBERT GIBSON.
